UNITED STATES PATENT OFFICE

2,567,801

HOT-WATER AIR HEATING UNIT

Eugene W. Caldwell, Maiden, N. C.

Application April 25, 1950, Serial No. 158,032

1 Claim. (Cl. 219—39)

1

This invention relates to heating units and more especially to an improved radiator type forced air heater.

The primary object of this invention is to provide an improvement in a hot water heater of a type having a radiator provided with pipes or tubes back of which a fan is disposed for circulating air through the radiator and having means for admitting water or the like to the pipes in the radiator under pressure, the improvement comprising an electrical heating element disposed within a container into which the water in the pipes is also admitted for heating the water in the pipes and an improved thermostatic regulator for said heating element.

There have, heretofore, been many heaters of substantially the type heretofore described which were provided with an electrically operable fan for circulating air past the pipes in the radiator and this fan being controlled by a suitable thermostat or the like. However, due to changes in temperature and atmospheric conditions, it sometimes happens that the fan will remain inoperative for a considerable length of time with the result that the pipes in the radiator will become overheated and the water or other fluid therein will evaporate thus causing the radiator pipes to give off an undesirable amount of heat and also causing the element to become overheated and to burn out and, of course, causing a relatively large consumption of electrical current resulting in costly operation of the heating unit.

It is, therefore, another object of this invention to provide a heater of the type described with an improved control means including a closed tube which projects into the container into which the water or other fluid in the pipes is also admitted and which is adapted to be submerged in the fluid, this tube having a rotatable shaft mounted therein and extending longitudinally thereof and being surrounded by a coiled spring, the other end of the closed tube relative to the container being slidably and rotatably penetrated by the shaft disposed within the tube and this shaft having suitable circuit breaking means on the outer end, such as one or more mercury switches, through which current passes from a source of electrical energy to the heating element disposed within the container.

The shaft within the closed tube is surrounded by a torsion spring, one end thereof being connected to the shaft and the other end being suitably secured in fixed relation to the tube. The torsion spring is responsive to changes in temperature so that upon the heating element in the

2

container having heated the water to a desired temperature, regardless of whether or not the fan is operating, the torsion spring will transmit partial rotation to the shaft which it surrounds to actuate the circuit breaking means to open the circuit to the heating element when the water or other fluid in the radiator pipes has reached a predetermined temperature, preferably, just below boiling point.

10 It is evident that, upon the temperature of the water or other fluid in the container being lowered to a predetermined temperature by the fan or through dissipation of the heat in the radiator pipes by any other means, the torsion spring will contract in such a manner as to again close the circuit to the heating element from the source of electrical energy.

Some of the objects of the invention having been stated, other objects will appear as the description proceeds when taken in connection with the accompanying drawings in which—

Figure 1 is a side elevation of the improved heating unit omitting the wall of the casing nearest the observer for purposes of clarity and showing many of the parts in cross-section;

Figure 2 is an enlarged elevation with parts in section, looking substantially along the line 2—2 in Figure 1, and showing a part of the improved control apparatus for the electrical heating elements;

Figure 3 is an elevation with parts in section looking substantially along the line 3—3 in Figure 1;

Figure 4 is a sectional plan view through the water heating container or manifold taken along the line 4—4 in Figure 3;

Figure 5 is an enlarged fragmentary sectional plan view taken substantially along the line 5—5 in Figure 1 and showing the apparatus responsive to the temperature of the water in the heater for controlling the flow of current to the electrical heating elements for heating the water;

Figure 6 is a diagrammatic view showing the various electrical parts of the apparatus schematically.

Referring more specifically to the drawings, there is shown a heating unit of a type such as is adapted to be suspended from the ceiling of a building, from a wall of the building or mounted on the floor. However, it is to be understood that the present invention may be used in association with many types of hot water radiator space heaters, the heating unit appearing in the drawings being shown by way of illustration only.

Referring to Figures 1 and 3, the numeral 10

broadly designates a radiator including a plurality of spaced vertically disposed tubes or radiator pipes 11 which penetrate a plurality of horizontally disposed and vertically spaced vanes 12 which are fixed to the radiator pipes 11 in the usual manner such as by soldering. The upper ends of the pipes 11 are suitably connected to and communicate with an upper manifold or container 15 which has an internally threaded adapter 16 secured thereto, as by welding at 17, 10 and communicating therewith.

A nipple 20 has one end thereof threadably embedded in the adapter 16 and the other end thereof is connected to an elbow 21 to which the upper end of a vertically extending pipe nipple 22 is threadably connected to a pipe elbow 23 to the other end of which a pipe 24 is threadably connected, this pipe 24 extending from a suitable source of fluid under pressure, such as water, for admitting water under pressure to the manifold 15 and the radiator pipes 11 as well as a lower manifold or container 30. The elbows 21 and 23 and the pipe nipple 22 form a trap so the heat of the water in the radiator 10 will not be transmitted to the pipe 24, since the heat of the water under pressure will not travel downwardly from the upper pipe 20. The manner in which the water is directed to the upper manifold 15 is a part of the present invention. The water is omitted from the drawings for purposes of 30 clarity.

The lower ends of the vertically disposed radiator pipes 11 are suitably connected to and communicate with the lower manifold 30. Both of the manifolds 15 and 30 are box-like in construction, being closed at all sides and at the upper and lower ends thereof. The lower manifold 30 includes left-hand and right-hand end walls 31 and 32, respectively (Figures 3 and 4), which are suitably connected to front and rear walls 33 and 34, respectively, the end walls 31 and 32 and the front and rear walls 33 and 34 being suitably connected to upper and lower walls 35 and 36, respectively.

A suitable pipe adapter 38 is secured, as by welding at 39, to the rear wall 34 and communicates with the lower manifold 30. This adapter 38 is adapted to threadably receive a pipe nipple 43 whose other end is threadably connected to a manually operable valve 44. This valve 44 has a discharge pipe 45 connected to its side remote from the side to which the nipple 43 is connected and the pipe 45 may be connected to a sewerage pipe line if so desired. The valve 44 may be opened for changing the supply of water in the radiator 10 and in initially admitting water to the radiator 10. The pipes 24 and 45 may support the heating unit if so desired or there may be suitable brackets, not shown, for mounting the heating unit. The manner of heating the water in the lower manifold 30 and the control means therefor will be later described in detail.

A suitable housing broadly designated at 50 is suitably secured at its lower end to opposed end walls 31 and 32 of the lower manifold 30, as at 51 (Figure 1), and its upper wall is also supported on the upper manifold 15, the upper manifold 15 having suitable nuts 52, only one of which is shown, secured thereto, as by welding, in which screws 53 are threadably embedded and which screws also penetrate the upper wall of the housing 50 for securing the same to the upper manifold 15.

The housing 50 has an opening 55 provided with suitable swingable louvres 56 which may be

adjusted in a conventional manner or which may be loosely pivoted to be swung open by a blast of air from a fan to be presently described. The rear of the housing 50 is closed by a rear wall 58 secured to the walls of the casing 50 as by bolts 59. The rear wall or panel 58 of the casing 50 has a suitable opening 61 therein through which the pipe nipple 20 extends. The rear panel 58 is also provided with a substantially centrally disposed circular opening 62 which is provided to permit a blast of air caused by a fan 63 to pass through the opening 62 and past the pipes 11 of the radiator 10 to thus transfer the heat from the tubes 11 through the opening 55 and between the louvres 56 and to discharge the same into the atmosphere.

The fan 63 is surrounded by a plurality of horizontally spaced guard rings 64 which vary in size and which are secured to a plurality of diagonally extending brace wires 66 of which only four are shown in Figure 3. These brace wires 66 are secured at their free ends as by screws 67, to the rear surface of the rear panel 58 and extend rearwardly and are suitably secured at their rearmost ends to an electric motor 70. The electric motor 70 has a shaft 71 extending forwardly therefrom and on which the fan 63 is fixedly mounted. The motor 70 also has electric wires 72 and 73 extending therefrom to a suitable source of electric energy in a manner to be presently described.

Referring to Figures 6, it will be observed that the wire 72 is connected at its end remote from the motor 70 to a lead wire 74 and the wire 73 is connected at its end remote from the electric motor 70 to a suitable manually adjustable electrically operable thermostat control apparatus 77 to the other side of which a wire 78 is connected. The end of the wire 78 remote from the thermostat 77 is connected to a lead wire 81 and, upon the circuit being completed by the manually adjustable thermostat, in a manner well known to those familiar with the art, the current will flow from the lead wire 81 through the wire 78, thermostat 77, wire 73, motor 70, wire 72 and lead wire 74 to complete the circuit to the electric motor 70 and to cause rotation of the shaft 71 and the fan 63. The heating unit as heretofore described is conventional and it is with this heating unit or a similar apparatus that the present invention is adapted to be associated.

Now, referring to Figures 3, 4 and 6, there will be observed a pair of spaced heating coils 85 and 86 which are of tubular construction and which have electrical heating elements or resistors 87 and 88, respectively, therein. The right-hand end wall 32 of the lower manifold 30, in Figure 4, has an opening, defined by the dotted lines 91 and 92, therein which is large enough to permit ingress and egress of the electrical heating coils 85 and 86 for installation purposes. This opening is covered by a reinforcing plate 93 suitably secured to the right-hand end wall 32 of the lower manifold 30 as by screws 94. The reinforcing plate 93 is slidably penetrated by a restricted portion 95 of a heating coil support member 96 suitably secured to the outer surface of the reinforcing plate 93 as by screws 97.

The heating coils 85 and 86 penetrate the heating coil support member 96 and the exposed ends thereof are bridged by suitable bus bars 100 and 101. These bus bars 100 and 101 are suitably connected, as by soldering, to the electrical heating elements 87 and 88 in the coils 85 and 86, respectively. Respective wires 102 and 103 are con-

nected to the bus bars 100 and 101 at one of their ends, their other ends being connected to respective closed tubular elements 104 and 105 of a mercury switch designated broadly at 106.

The closed tubular elements 104 and 105 contain an electrically conductable fluid such as balls of mercury 107 and 108, respectively, which, when the tubular elements 104 and 105 are in the tilted position, shown in Figures 3 and 6, will complete a circuit between the wires 102 and 103 and respective wires 111 and 112 which are also suitably connected to the closed tubular elements 104 and 105. The ends of the wires 111 and 112 remote from the closed tubular elements 104 and 105 are connected to a lead wire 114 and the lead wire 81, respectively. A wire 115 is connected intermediate the ends of the wire 111 and is connected at its other end to the lead wire 74.

The mercury switch 106 includes a plate member 120 having a hub portion 121 (Figure 5) integral therewith which is slidably penetrated by an enlarged portion 122 of a shaft 123 and is secured on this enlarged portion 122 by a set screw 124. The plate 120 has suitable spring clips 126 projecting outwardly therefrom within which the closed tubular elements 104 and 105 are clampingly secured.

The shaft 122 is oscillatably mounted in a hub portion 127 of an adjustable control member 130 which has an upwardly projecting portion 131 (Figure 2) integral therewith provided with an arcuate slot 132 therein which is penetrated by an adjustment screw 133 for securing the control member 130 in adjusted position on a vertically disposed plate 134. The vertically disposed plate 134 has suitable graduations 135 or other indicia thereon to determine the proper position for the control member 130, this control member 130 being adapted to control the heat of the water or other fluid in the lower manifold 30 in a manner to be later described. The plate 134 is mounted in adjusted position between a pair of lock nuts 136 and 137 threadably mounted on an enlarged portion 140 of a tubular member 141 which extends into the lower manifold 30 and is closed at its inner end as at 142. This inner portion of the tubular member 141 is adapted to be submerged in the water in the lower manifold 30, however, the water does not enter the tubular member 141.

The rear wall 34 of the lower manifold 30 has a second pipe adapter 143 suitably secured thereto, as by welding at 144 (Figure 5), and the rear end of this adapter 143 is threaded for reception of a second adapter or pipe reducer 145 which threadably receives the enlarged portion 140 of the tubular member 141. It is thus seen that the plate member 134 is supported by the tubular member 141 which is, in turn, supported by the rear wall 34 of the lower manifold 30.

The hub portion 127 of the control member 130 is slidably fitted in the tubular member 141 and has a restricted portion 147 integral therewith which is surrounded by one end of a torsion spring 150, this torsion spring 150 being connected at one end to the restricted portion 147 of the hub 127 by any suitable means such as a screw 151. In order that the torsion spring 150 may be properly sensitive to changes in temperature, it is preferable that this torsion spring 150 be of a flat wire material and of considerable length relative to its diameter. The other or right-hand end of the torsion spring 150, in Figure 5, is suitably secured to the right-hand end of the shaft 123, this shaft 123 being slotted as

at 153 for reception of the right-hand end of the torsion spring 150. The walls of the slot 153 are held in engagement with the right-hand end portion of the torsion spring 150 by any suitable means such as a cotter pin 154.

In operation, the manually adjustable thermostat 77 is adjusted to the desired room temperature and when the room is below the desired temperature the current will flow to the electric motor 70 in the manner heretofore described to cause rotation of the fan 63 and to cause air to circulate between the vanes 12 and past the radiator pipes 11 to be discharged through the opening 55 between the louvres 56 into the surrounding atmosphere for discharging heat from the pipes 11.

The control member 130 is also adjusted to the desired temperature for the water or other fluid within the radiator 10, it being evident that it will not be necessary to heat the water to as high a temperature during relatively warm atmospheric conditions as it will during relatively cold atmospheric conditions. The control mechanism for controlling the heat of the water in the radiator 10 may be adjusted by loosening the screw 133 and rotating the control member 130 to the desired temperature as indicated on the plate 134. This will, of course, increase or decrease the existing torsion in the torsion spring 150.

Assuming the water or other fluid in the lower manifold 30 to be below the desired temperature, the closed tubular elements 104 and 105 of the mercury switch 106 will be disposed in substantially the position shown in Figures 3 and 6 and this will permit current to flow to the heating elements 87 and 88 in the water heating coils 85 and 86. A circuit will be completed to the heating elements 87 and 88 from the lead wires 114 and 115, through the wire 111, the mercury ball 107, wire 102, through the bus bar 100, to one end of both of the heating elements 87 and 88 and then through the bus bar 101, wire 103, mercury ball 108 in the closed tubular element 105 and wire 112 to the lead wire 81 thus completing the circuit to the electrical heating elements 87 and 88.

It is not essential that there be two closed tubular elements, such as the elements 104 and 105, as it is evident that a single switch means will operate satisfactorily in completing a circuit to the electrical heating elements 87 and 88 it merely being necessary to change the arrangement of the wiring in a manner well known to anyone skilled in the art.

The heating coils 85 and 86, having the heating elements 87 and 88 therein, will then heat the water in the lower manifold 30 as well as the pipes 11 and the nipple 20. Inasmuch as the water or other fluid is directed to the radiator 10, including the upper manifold 15, through the pipe 24 under pressure, as heretofore stated, by offsetting the pipe 24 relative to the nipple 20, and the pipe 24 being positioned at a lower elevation than the pipe 20, the water or other fluid in pipe 24 will not travel downwardly through an off-set pipe to the pipe 24.

Now, when the temperature of the water in the lower manifold 30 has reached a predetermined temperature, according to the position of the adjustable control member 130, the torsion spring 50 will expand due to this change in temperature and will thus partially rotate the shaft 122 in a clockwise direction in Figure 3 and, in so doing, will cause the mercury switch 106 to ro-

tate in a like manner to where the closed tubular elements 104 and 105 will be disposed in a substantially level position or will extend at an angle opposite from the angle at which they are shown in Figures 3 and 6. This will result in the mercury balls 107 and 108 in the closed tubular elements 104 and 105 moving out of engagement with the corresponding wires 102 and 111 and 103 and 112 thus opening the circuit from the lead wires 81, 114 and 115 to the electrical heating elements 87 and 88 in the heating coils 85 and 86 until the temperature of the water in the lower manifold 30 will have lowered sufficiently to where the spring 150 will again contract and will transmit partial counterclockwise rotation to the shaft 122 to again tilt the closed tubular elements 104 and 105 to substantially the position shown in Figures 1, 3, and 6.

It is thus seen I have provided an improved control means for automatically controlling the flow of current to electrically operable heating elements in accordance with the temperature of the liquid which the heating elements are adapted to heat and wherein the control apparatus is adjustable according to the desired temperature of the water or other liquid in the lower manifold 30 of the heating unit. The switch 106 is adjustable on the end of the shaft 122 to produce a desired sensitivity in reaction of the control apparatus in affecting the flow of current to the electrical heating elements 87 and 88. Although it is not necessary, the torsion spring 150 may be made of a bi-metallic material if so desired to thereby increase its sensitivity to changes in temperature.

In the drawings and specification there has been set forth a preferred embodiment of the invention and, although specific terms are employed, they are used in a generic and descriptive sense only and not for purposes of limitation, the scope of the invention being defined in the claim.

I claim:

An improved temperature regulator in a space heater, said space heater having upper and lower water containing manifolds, means connecting said manifolds, said space heater also being provided with means for introducing water under pressure into said manifolds and said space heater

also having a frame, said improvement comprising at least one heating coil positioned within said lower manifold and having the free end thereof insulatably mounted in one of the walls 5 of said lower manifold, a bracket secured to said frame adjacent said lower manifold, a closed tubular member fixedly mounted in said bracket and extending within said lower manifold, a gauge member adjustably mounted in the end of said 10 tubular member extending from said lower manifold, a shaft rotatably mounted in said gauge member and extending within said tubular member, a coiled thermostatic element positioned within said tubular member and about said shaft and having one of its ends connected to said shaft and the other of its ends connected to said gauge member, a switch bracket secured to the outer end of said shaft, at least one clip secured to said switch bracket, a mercury tube positioned in said clip, a source of electrical energy, an electrical circuit connecting said mercury tube with said source of electricity and with said free end of said heating coil, said circuit being broken at said mercury tube, said mercury tube having 20 mercury therein adapted to close said circuit upon said tube being moved to switch closed position, whereby heat in said lower manifold will cause said shaft to rotate a predetermined amount to move said mercury tube to switch open position and upon said lower manifold cooling, said shaft will rotate in the opposite direction to move said mercury tube to switch closed position to actuate said heating coil to heat the water in said lower manifold.
